UNITED STATES PATENT OFFICE.

FREDERICK W. SCHROEDER, OF LONDON, ENGLAND, ASSIGNOR OF ONE-HALF TO PATRICK WILLIAM MORAN, OF SAME PLACE.

DRIVE-CHAIN.

SPECIFICATION forming part of Letters Patent No. 650,591, dated May 29, 1900.

Application filed August 18, 1899. Serial No. 727,723. (No model.)

To all whom it may concern:

Be it known that I, FREDERICK WILLIAM SCHROEDER, a citizen of the United States of America, residing at No. 30 Maiden Lane, 5 Strand, London, England, have invented certain new and useful Improvements in Drive-Chains, (for which application for a patent in Great Britain has been made, dated June 7, 1899, No. 11,824,) of which the following is a 10 specification.

This invention relates to an improved construction of chain and chain-wheel-driving gear, whereby, on the one hand, the frictional wear of the chain in working on the chain-wheel is in great measure prevented, and, on the other hand, the construction of the chain is such that defective links can be readily removed and replaced by new ones. For these purposes instead of making the transverse 15 pins that connect the side links of the chain of cylindrical form I make them, with the part between the links, of spherical form, and I make the teeth of the chain-wheel with corresponding concave surfaces where the 20 spherical pins work over them. By this means the chain is maintained in a perfectly-central position when passing over the wheel, and consequently all lateral shifting and frictional contact between the links and the side 25 surfaces of the teeth is prevented. I will describe the construction of the chain with the said spherical pins with reference to the accompanying drawings.

Figure 1 shows a plan of one of the spherical 30 pins detached. Fig. 2 shows a part-sectional plan of the same connected with a second pin by two side cheeks to form a link. Fig. 3 shows a plan of the link combined with connecting-plates by means of connecting-pins. 35 Figs. 4 and 5 show a plan and an end view of one of the connecting-pins. Fig. 6 shows a side view of the links, and Fig. 7 shows the links in the position necessary for enabling them to be separated.

In the construction shown at Figs. 1 to 6 the pins are formed with a spherical middle 40 part *a* and cylindrical ends *b*, and they have a cylindrical hole *c* formed through them. Onto the cylindrical ends *b* are fitted loosely 45 the side cheeks *d*, so that the pins can revolve in them, and through the holes *c* are passed cylindrical pins with notched ends *e*, with which engage the slotted connecting-links *f*, that serve to connect the links, with 50

spherical pins, together. These connecting-links *f* and the notched pins *e* are constructed in a known manner, not forming part of this invention—that is to say, the middle of the slot of *f* is made sufficiently wide for the pin to pass through, while the narrower ends of the link are adapted to fit the notches of the ends of pins *e*, so that when these have been slid into the end position they are securely held by the connecting-links *f*.

It will be seen that the parts are so proportioned that when the links are in the extended position, as at Fig. 6, the pins *e*, with their spherical pins *a*, cannot move inward a sufficient distance to enable them to assume the middle position in the enlarged slot and 60 that consequently no accidental detachment of the pins *e* and connecting-links *f* can take place in working. It is only when the two adjacent link portions *a d e* are turned into a position at right angles to the connecting-links *f*, as shown at Fig. 7, that first one of the link portions *a d e* can be moved into the middle position, (shown in dotted lines,) so that the pin *e* can be drawn out, and consequently 65 the parts *a d* detached from *f*, after which 70 the second link can be removed in the same manner. Thus while the chain constructed as above described has its links effectually secured together while in the working position the parts can be readily separated when 75 the links are brought into the position at Fig. 80 7, and a defective link can then be replaced by a new one.

Having thus described the nature of this invention and the best means I know of carrying the same into practical effect, I claim—

In a driving-chain, the combination of tubular pins, each having a spherical surface *a* on its middle part, and cylindrical ends *b*, side cheeks *d* having holes arranged to receive said cylindrical ends, solid pins *e* with notched ends passing through the tubular pins, and connecting-links *f* having slots with narrowed ends arranged to fit the notches of the pins *e*; substantially as described. 95

In testimony whereof I have hereunto set my hand in presence of two subscribing witnesses.

FREDERICK W. SCHROEDER.
